MAKE-UP PROTECTOR MASK

Bella Klein, New York, N. Y.

Application March 21, 1946, Serial No. 655,951

4 Claims. (Cl. 2—174)

1

This invention relates in general to a protective mask and in particular to a mask for protecting the face of a wearer from brushing contact with external articles, and conversely for protecting said articles from contact with the face of the wearer.

It is well known that clothing stores, particularly women's clothing stores are constantly faced with damage to merchandise caused by soiling and staining when clothing is tried on by prospective buyers. The soiling is principally a result of cosmetics and make-up from the customer's face being smeared onto the clothing while it is being slipped over the customer's head.

In addition, it is equally well known that women frequently prefer to apply various cosmetics to their faces before they finish dressing, so that make-up is not spilled onto their outer clothing. Inasmuch as the clothing is subsequently slipped over the head, there is great danger of soiling the clothing from the freshly applied make-up, with the simultaneous and consequent smearing of the make-up.

Accordingly it is an object of this invention to provide a protective mask to protect against accidental contact between a wearer's face and an external object.

It is another object of this invention to provide a protective mask to protect against a brushing contact between a wearer's face and clothing being slipped over the wearer's head.

Additional objects of the invention as well as the construction and use thereof will in part be obvious and will in part become apparent from the following disclosure:

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view of a mask according to one form of the invention.

Fig. 2 is a side elevational view of the article of Fig. 1.

Fig. 3 is a top cross sectional view of the article shown in Fig. 2, taken along the line 3—3.

Fig. 4 is a plan view of a blank from which is made the article shown in the previous figures.

Fig. 5 is a perspective view of a mask according to a further form of this invention.

Fig. 6 is a top plan view of the article shown in Fig. 5.

2

Fig. 7 is a perspective view of a mask according to a still further form of the invention.

Fig. 8 is a perspective view showing the fastening means of the mask.

Referring to the figures in detail, there is shown in Fig. 1 a mask generally designated 10 comprising a pair of face pieces 11 secured to one another along a substantially vertical middle line 12, having a binding or frame 13 therearound, and having a plurality of strings or tying members 14 extending from the corners thereof. Various structural details and features of the mask are shown in Fig. 1 and in Figs. 2 to 4.

The face pieces or blanks 11 comprise a flexible sheet member, preferably either transparent or at least translucent and cut to conform at least roughly with the contour of a wearer's face. The blank 11 is optionally constructed of an impregnated cloth or a flexible sheet plastic, such as a sheet of Cellophane, semi-transparent treated cloth, synthetic plastic, or the like, preferably being of a clear colorless appearance and of a clean, fresh texture. One of the purposes of the mask according to this invention is to inspire in the wearer a feeling of cleanliness; this can readily be heightened by a suitable choice of construction material, the proper selection of which will be obvious to those skilled in the art.

As shown in the figures, one of the edges of the blank 11, namely the front edge, is substantially higher or longer than the other edge, whereby the mask tapers towards its ends, and whereby full protection is provided for the front of the face whereas a convenient tying portion is provided and is adapted to be fitted toward the back of the wearer's head. The front edge 12 of this blank is curved or tapered outwardly, to conform with the face of the wearer, the curvature terminating in a forwardly extending projection 15 adapted to form a nose piece. Optionally an eye hole 16 (shown in dotted outline in Fig. 4) is located in the blank somewhat above and to the rear of nose piece 15. It will be understood, of course, that the eye hole 16 is optional especially when the mask is formed of a truly transparent material, although for greater simplicity and universality of disclosure an eye hole is included in the various figures.

The body or face of the mask is formed by two of these blanks 11 being secured together along their front edges 12. Where the mask is constructed of a material uniform throughout and similar on both surfaces, the two blanks 11 will be identical in shape; where one surface differs from the other, one blank 11 will be a mirror

image of the other whereby one is adapted to form the left side of the mask whereas the other blank forms the right side of the mask. An edging or binding 13 is secured substantially around the periphery of the mask, for example by means of stitching 17. As indicated in Fig. 3, this binding comprises a tape or the like folded around the edge of the mask and secured in place by means of conventional stitching.

The eye holes 16 are similarly protected against tearing or distortion by means of further stitching; optionally and alternatively, the eye holes 16 may be protected by means of a binding similar in structure to the border binding 13 (not thus shown in the figures). The binding and/or stitching around the eye holes 16 and around the edge of the mask serve the various purposes of preventing destruction of the mask, preserving the shape from pulling and stretching, and in the case of the border stitching providing an anchoring means for the tying strings 14 which extend from the corners of the mask.

In the form of the invention shown in Figs. 1 to 4, there are four tying strings 14 on the mask, one extending from each corner. These tying strings are constructed, for example, of tape material similar in structure to the binding tape 13; in fact, in the preferred form of this invention, it is understood that these tying members may be simply integral extensions of the binding tapes 13.

In the presently preferred form of the invention, care is taken in securing together the two blanks 11, to insure that the extending edges 18 (see Fig. 3) extend inwardly; i. e. the blanks are placed together with their outer or forward surfaces facing one another, the blanks stitched together, and the mask then turned right side out, leaving the edge of the seam facing inwardly. In this way it is insured that there will be no rough seam edges projecting to catch on clothing as it brushes past.

The use of the article shown in Figs. 1 to 4 is apparent from the figures themselves with the description included hereinbefore. The mask is simply placed over the face of the wearer, strings 14 are properly tied behind the wearer's head or in another convenient place, whereby the wearer's face is safely and securely protected. With this mask in position, the wearer is now free to slip clothing over her head without fear of damage either to the clothing or to her make-up because of contact therebetween. The mask is comfortable to the wearer inasmuch as it is constructed to conform loosely with the contours of the face, and is entirely free from sharp edges or surfaces which might damage the finest and sheerest of clothing.

In Figs. 5 and 6 is shown another form of this invention comprising a mask 10^a comprising two face pieces 11^a secured together and having a border binding 13^a therearound, all in a manner and construction similar to that set forth in connection with the previous figures. Extending from one side of the mask, and secured thereto in convenient manner, for example by means of stitching of the line, is at least one fastening member or string 14^a. This string 14^a is adapted to be releasably secured to the other end of the mask by means of a snap fastener 19^a. Fig. 8 shows such a fastener 19^a mounted on the corner of one end of the mask to the border binding 13^a and to the string 14^a.

By means of this fastener and string 14^a, the mask is adapted to be quickly and readily secured around the face of a wearer. In order to provide

maximum of versatility of size, it is contemplated that the tying or fastening string 14^a will be constructed of a stretchable material such as a conventional elastic band or covered elastic, whereby a large flexibility of size is afforded.

In Fig. 7 there is shown a further form of the invention in which there is provided a head covering or hair covering 20 which is secured along at least a part of the upper edge of the mask. 10 The mask is similar in structure to either of the previously set forth forms of the invention, the hair cover 20 being optional with either form. This hair cover 20 is secured across the front of the mask and optionally partly along the side, and extends over the top of the head of the wearer and part way down the back of the head, thus providing a hair protector integrally mounted on the mask. This form of the invention is particularly useful for a woman who prefers to apply her make-up and to fix her hair prior to putting on her outer clothing, thus avoiding dropping powder, loose hair, or the like on the clothing, and it permits her to do this without subsequently disturbing the careful arrangement of her hair as she slips clothing over her head. Additionally, this form of the invention is useful in preventing various customers in a clothing store from passing to one another various communicable scalp diseases.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A protecting mask for preventing contact between a wearer's face and hair and clothing being slipped over the wearer's head, comprising a pair of face pieces shaped to conform with a wearer's face leaving free neck, side and hair portions and secured together along the front edges of said face pieces, a binding secured around the edges of said face pieces to form a chin line, a cheek line and a hair line, and fastening members extending from the edges of said mask for securing the mask on the face of the wearer, and a hair cover secured across the front of the mask and the top thereof to said hair line only and otherwise unengaged, said hair cover being adapted to extend over the top of the wearer's head and at least partially down the back of the wearer's head to cover the wearer's hair.

2. A protecting mask for preventing contact between a wearer's face and hair and clothing being slipped over the wearer's head, comprising a pair of face pieces shaped generally to conform with the wearer's face leaving free neck, side and hair portions and stitched together along the front edges of said face pieces with an inwardly extending seam, a binding stitched around the edges of the mask to form a chin line, a cheek line and a hair line, and tying strings extending from the binding for securing the mask on the face of the wearer, and a hair cover secured across the front of the mask and the top thereof to said hair line only and otherwise unengaged, said hair cover being adapted to extend over the top of the wearer's head and at least partially down the back of the wearer's head.

back of the wearer's head to cover the wearer's hair.

3. A protecting mask for preventing contact between a wearer's face and hair and clothing being slipped over the wearer's head, comprising a pair of face pieces shaped generally to conform with the wearer's face leaving free neck, side and hair portions, each face piece having a projecting nose piece substantially at the center of the front edge thereof and having an eye hole located behind and above said nose piece to correspond in position with the wearer's eye, said face pieces being stitched together along the front edges of said face pieces with an inwardly extending seam, a binding stitched around the edges of the mask to form a chin line, a cheek line and a hair line, and tying strings extending from the binding for securing the mask on the face of the wearer, and a hair cover secured across the front of the mask and the top thereof to said hair line only and otherwise unengaged, said hair cover being being adapted to extend over the top of the wearer's head and at least partially down the back of the wearer's head to cover the wearer's hair.

4. A protecting mask for preventing contact between a wearer's face and hair and clothing being slipped over the wearer's head, comprising a pair of face pieces shaped generally to conform with the wearer's face leaving free neck, side and hair portions, each face piece having a projecting nose piece substantially at the center of the front edge thereof and having

an eye hole located behind and above said nose piece to correspond in position with the wearer's eye, said face pieces being stitched together along the front edges of said face pieces with an inwardly extending seam, a binding stitched around the edges of the mask to form a chin line, a cheek line and a hair line, and at lease one fastening member extending from one end of said mask and being adapted to be releasably secured to the other end of said mask to fasten the mask across the face of the wearer, and a hair cover secured across the front of the mask and the top thereof to said hair line only and otherwise unengaged, said hair cover being adapted to extend over the top of the wearer's head and at least partially down the back of the wearer's head to cover the wearer's hair.
